United States Patent Office

Des. 224,091
Patented July 4, 1972

224,091

DISPENSING TOP FOR A CONTAINER

Peter Swartzbaugh, Toledo, Ohio, assignor to Abbott
Laboratories, North Chicago, Ill.

Filed Nov. 10, 1970, Ser. No. 25,923

Term of patent 14 years

Int. Cl. D9—07

U.S. Cl. D9—257

FIG.1

FIG.3

FIG. 1 is a top plan view of a dispensing top for a container showing my new design;

FIG. 2 is an edge view;

FIG. 3 is a bottom plan view;

FIG. 4 is a top perspective view in open position; and

FIG. 5 is an edge view in open position.

The broken lines showing a container or a portion of a container in FIGS. 2, 4 and 5 are for illustrative purpose only.

I claim:

The ornamental design for a dispensing top for a container, substantially as shown and described.
